200,660

COMBINED DOOR LOCK HOUSING AND HANDLE THEREFOR

Berwyn E. Etter, 3120 40th Ave. N., St. Petersburg, Fla.

Filed Apr. 17, 1964, Ser. No. 79,559

Term of patent 14 years

(Cl. D50—5)

I claim:

The ornamental design for a combined door lock housing and handle therefor, substantially as shown.
